UNITED STATES PATENT OFFICE

2,424,102

SEWING MACHINE

Harold J. Le Vesconte, Glendale, Calif., and Albert M. Schweda, Chicago, Ill., assignors to Union Special Machine Company, Chicago, Ill., a corporation of Illinois

Application May 9, 1944, Serial No. 534,718

8 Claims. (Cl. 112—218)

1

This invention relates to an improved sewing machine structure and more particularly to an improved combination of a sewing machine with a driving motor and clutch unit, all associated with a suitable supporting structure. More particularly the invention relates to the provision of simple and readily accessible means, in combination with the motor and clutch unit, for producing a stream of cooling air and directing the same against or into the path of the stitch forming means, for the purpose of increasing the permissible speed of operation of the sewing machine.

A primary object of the invention has been to provide a sturdy and efficient, but economical, blower and associated devices in conjunction with a motor and clutch unit in such a way and of such character that the parts may be readily assembled and taken apart.

Another object of the invention has been to provide a construction of the character indicated which enables the rapid application, removal or replacement of the driving belt which connects the motor and clutch unit with the pulley of the sewing machine. This arrangement is such that the blower or other means provided for creating the desired blast or stream of air need not be disturbed in the course of applying and removing the driving belt.

A special feature of the improved construction is the provision of simple but effective means for enabling relative adjustment between the housing and rotor of a blower employed for the production of the blast or stream of air. The blower housing is fixedly mounted upon the frame of the motor and clutch unit while the rotor is mounted for simple axial adjustment along the driven shaft of the motor and clutch unit, this shaft being shifted axially of the frame structure to effect engagement and disengagement of the clutch. Due allowance is thus provided, and compensation is quickly and readily made, for wear of the clutch surfaces so that the danger of direct engagement between the rotor and housing of the blower may be readily avoided at all times.

Another feature of the improved construction is the formation of the parts of the blower in such manner that they are adapted for either clockwise or counter-clockwise rotation of the rotor or impeller. The construction in this respect is such that the blower housing may be mounted on the supporting structure in either of two positions, in reversed relation to each other. The rotor may also be reversed, if de-

2

sired, but its reversal is not required for rotation in opposite directions.

A further special feature of the construction is the provision of an improved form of operating means for shifting the driven member of the clutch into engagement with the driving member. This means is mounted directly upon the motor and clutch unit and forms a unitary part of it. It is also readily detachable from the unit, either separately or with a portion of the frame and the driven member of the clutch. Moreover, the construction is such that the position of certain parts of the operating train may be adjusted or altered so as to vary the position and the range of movement of the operating lever. Compensation may thus be made for wear of the parts and for other conditions calling for a change in the range or zone of movement of certain parts.

A still further feature of the improved construction is the arrangement of the outlet of the blower in such a way that it will be moved substantially vertically in the adjustment of the motor and clutch unit to vary the tension of the driving belt.

25 Other objects, features, and advantages of the invention will appear from a detailed description of an illustrative form of the same which will now be given in conjunction with the accompanying drawings, in which:

30 Fig. I is a view in side elevation, with parts broken away for clarity of illustration of other parts, showing a sewing machine and its associated motor and clutch unit in assembled relation on a supporting table, the latter being shown only in part.

Fig. II is an end elevation of the construction shown in Fig. I.

Fig. III is an enlarged sectional view taken axially through the clutch portion of the motor and clutch unit.

40 Fig. IV is an enlarged view, partly in end elevation and partly in vertical section, showing the motor and clutch unit as viewed from the right in Fig. III, the driving pulley being removed, and

45 Fig. V is a detail view, partly in plan and partly in horizontal section, showing a removable sub-assembly forming a portion of the clutch unit and related parts.

Referring now to the drawings, there is shown 50 in Figs. I and II a supporting table 10, which may be of any suitable construction, mounted on an appropriate framework or leg structure serving to position the top of the table at a desired elevation. A sewing machine 11 of a conventional type is mounted on the table and a motor

and clutch unit 12, commonly designated an electric transmitter, is mounted on the underside of the table top. A belt 13 connecting a pulley 14, forming part of the electric transmitter, with a pulley 15 on the main shaft of the sewing machine, provides an appropriate drive for the latter, as will appear more clearly hereinafter. The sewing machine is adapted to be driven whenever the clutch of the electric transmitter is engaged. While the sewing machine may be of any suitable conventional type, the one illustrated is of a kind having a work supporting base structure 16 with an upwardly extending standard 17 adjacent one end, this standard carrying at its upper end a horizontally extending, overhanging arm 18. At its outer end the arm carries a needle head in which is mounted a vertically reciprocable needle bar 19 carrying one or more needles 20. In the operation of the machine, the operative ends of these needles are carried from a point well above the work support to a point in which the thread carrying eyes are below the work support in position to cooperate with complementary stitch forming means, such as loopers 21. Suitable connections, not shown, are provided from the main shaft to which the combined pulley and hand wheel 15 is secured for operating the needle bar 19 and the loopers 21. Also, within the base 16 there is provided suitable work feeding mechanism such as a feed dog or the like, not shown, adapted to be given a four motion movement by suitable connections from the main shaft. Cooperating with the feed dog is a presser foot 22 carried at the lower end of a presser bar 23 which is vertically slidable in the needle head and urged downwardly under a variable pressure by means of a spring 23a. It will be understood that the usual accessories are provided, such as means for supplying and guiding the necessary thread to the various stitch forming devices and suitable means for effectively lubricating the various operating parts. Since the sewing machine proper is of conventional form, it need not be described in further detail. Reference may be had, however, to the patent to Thompson, et al., No. 2,107,918, granted February 8, 1938, for fuller disclosure of a suitable construction.

The transmitter includes a motor 24 having integral with the right hand end bonnet (Fig. I) a frame structure 25 which, as shown in Figs. II and IV, may suitably be of V configuration in end elevation. This construction, in general, may be similar to that disclosed in the application of Harold J. Le Vesconte and Albert M. Schweda, S. N. 449,196, filed on June 30, 1942. However, the construction disclosed in said prior application has been modified to incorporate certain improvements forming part of the present invention.

Extending rearwardly from the frame 25 are two ears 26 (only one being shown, Figs. II and IV) having pivotal connection with the lower ends of arms 27 (one being shown) extending rearwardly and downwardly from a supporting plate 28 attached by screws or the like to the undersurface of the table 10. Swivelly mounted in forwardly extending ears on the plate 28, is a bolt 29 which cooperates with the forked outer end of an arm 30 projecting upwardly and forwardly from the frame 25. Nuts 31, disposed above and below the arm 30, are adapted to retain the frame in any desired position in relation to the bolt 29. This allows for the proper tensioning of the belt 13 and for the ready application of a new belt in the event of breakage.

Referring now to Fig. III, the motor 24 has an armature shaft 32 journaled at its righthand end in a ball bearing 33 mounted in a transversely extending wall 34 of the end bonnet. Secured to the outer end of the shaft 32, for rotation therewith, is a flywheel 35. On the outer surface of the flywheel there is secured in any suitable way, a friction member 36 of annular form having an inner frusto-conical face. This conical face cooperates with a corresponding outer conical face on a driven clutch member 37 secured to a shaft 38, which is in axial alinement with the shaft 32. Shaft 38 is mounted in ball bearings 39 and 40 carried by a sleeve 41 which is slidably mounted in a cylindrical portion 42 of the frame 25. This cylindrical portion of the frame is of split construction and is provided with a lower half or cap member 43 which may be readily detached. Cap member 43 is secured to the upper main portion of the frame by a series of screws 44. The pulley 14 is secured to the outer end of the shaft 38 by means of a nut 45 and has a splined connection with the shaft.

The lower portion of the sleeve 41 is provided with a series of circumferentially extending grooves and ribs forming rack teeth 46 adapted to cooperate with corresponding teeth 47 forming a pinion at the inner end of a rotatable stud 48, mounted for rotation within a pocket provided by a downwardly extending portion 49 of the lower cap member 43. An annular groove 50 extending around the stud 48 is adapted to cooperate with a pin 51 carried by the part 49 to hold the stud against axial movement within the pocket. At its outer end the stud is cut away, as best shown in Figs. I and IV, to provide a crosslike configuration 52. The outer ends of the arms of the cross form a part of the same cylindrical surface as the main body of the stud and they are surrounded by a split sleeve or collar 53 adapted to be clamped about the ends of the cross by means of a screw 54. Integral with the collar is an operating arm 55 having an offset portion 56, this arm being adapted for connection with a treadle or a knee control. For the purpose of providing a positive driving connection between the collar 53 and the cross-like formation 52, the collar 53 carries a pair of set screws 57. The ends of these set screws are adapted to engage opposite faces of one of the arms of the cross. By proper adjustment of the set screws the relative angular position of the collar 53 on the cross formation may be varied, as desired, within limits. A greater adjustment in the angular position of the operating arm 55 may be made by partially withdrawing the stud 48 and rotating it, while out of mesh with the rack teeth 46, and then meshing a new set of teeth. If an adjustment of nearly 90° is desired, the set screws may be arranged to cooperate with another arm of the cross member. In making any readjustment of the collar on the cross member the screw 54 will first be loosened. As will be seen, the operating force is transmitted between the collar 53 and the member 52, both frictionally due to the clamping action of the screw 54 and positively due to the action of the set screws 57.

In the preferred position of the parts the arm 55 is disposed substantially horizontally at a level just below the axis of the stud 48. A spring 58 connected at one end with the offset portion 56 and at its other end with a stud 59, carried by the frame 25, tends to rock the arm 55 and its connected collar 53 in a clockwise direction, Fig. I. Thus, the spring 58 tends to shift the sleeve 41 to-

ward the right, Fig. III, in which the clutch member 37 is disengaged from the friction surface of the flywheel 35. At this time the right-hand face of the clutch member 37, Fig. III, may be held in engagement with a brake surface 59, Fig. I, which may be adjusted in the manner disclosed in said pending Le Vesconte-Schweda application.

We come now to the improved construction for creating a blast or stream of cooling air and directing the same through the region or zone in which the needles are operated above the work support. For this purpose there is mounted upon an axially extending hub or sleeve portion 60 of the driven clutch member 37 (Fig. III) a rotor or impeller forming part of a blower. This rotor comprises a hub member 61 secured by a set screw 62 to the extension 60 and having a blade carrying disc 63 secured thereto by means of screws 64. The blade carrying disc of the impeller may be formed in any suitable way but it is preferably simply a flat sheet metal disc having a central opening and having welded or otherwise secured to one face a series of angle members 65. Surrounding the impeller there is provided a housing 66 having an appropriate clearance with respect to the impeller to allow for the axial movement of the latter in the engagement and disengagement of the clutch and yet provide an efficient blower construction. As best shown in Fig. II, the clearance space around the periphery of the impeller is of gradually increasing radial extent in the direction of rotation of the impeller. This will result in the efficient generation of a stream of air to be discharged through the outlet passage 67 of the blower. The housing 66 is preferably formed by a casting 66a, which provides one of the sides of the housing and also the outer peripheral wall 66b of the housing. The other side wall is formed by a plate 66c secured by screws 66d to the flange forming the peripheral wall 66b of the housing. Both the member 66a and the plate 66c are provided with central openings 66e of sufficient size to provide ample clearance with respect to the hub member 61 of the impeller and the end of the sleeve 41, as shown in Fig. III. It will be apparent that this arrangement is such that the housing may be arranged either as shown in Figs. II and III or in the reverse position in which the opening in the member 66a will receive the hub of the impeller and the plate 66c will receive the end of the sleeve 41. Thus, the housing may be positioned as shown in the drawings for a motor driven in a counter-clockwise direction, Fig. II, and may be arranged in the reverse position for a motor driven in a clockwise direction. The impeller is preferably mounted in the same position as indicated in Fig. III, regardless of the position of the housing, although its direction may be reversed, if desired, and the blades 65 may be extended over the hub 61 rather than away from the latter.

The blower housing is mounted, by means of a pair of screws 68, upon a pair of laterally extending ears 69 projecting outwardly from the cap member 43, which partially encloses the clutch shifting sleeve 41. The screws 68 cooperate with threaded openings in the side wall of the housing member 66a. Opposite these threaded openings the plate 66c is also provided with threaded openings normally closed by plug screws 70. It will be understood that when the blower housing is mounted in the reverse position, the screws 68 will cooperate with the threaded openings in the plate 66c, while the plug screws 70

will then be carried by the threaded openings in the member 66a.

It will be seen from the foregoing that the blower housing may be readily connected with or disconnected from the frame of the electric transmitter unit. Furthermore, the entire assembly illustrated in Fig. V may be readily assembled or disassembled in relation to the rest of the transmitter unit. It is simply necessary for disassembling purposes to remove the four screws which attach the cap member 43 to the frame member 42. This will allow the cap member to be removed along with the sleeve 41 and the shaft 38 with all of the connected parts. Sufficient clearance is provided to enable the necessary axial movement of the parts mentioned to insure disengagement of the clutch members 35 and 37 in the disassembly operation described. Note particularly the clearance between the top of the blower housing and the transmitter frame.

The current of air developed by the blower is delivered by the outlet extension 67 to a coupling member 71, Fig. II, which is preferably formed of rubber or suitable plastic having a certain amount of flexibility and elasticity. The coupling member 71 may suitably have a portion of rectangular cross-section at its lower end adapted to fit over the end of extension 67. This rectangular portion of member 71 merges into a cylindrical portion at the upper end, which is adapted to fit over the lower end of a tube 72, formed of metal or similar material. This tube extends upwardly through an opening 73 in the table and thence over the region of operation of the needles of the sewing machine. Within the opening 73 the tube may be held by a bushing 74 having a flange supported by the upper surface of the table. A collar 75 secured to the tube rests upon the upper arm of an extension 76 of the bushing. Both the collar 75 and the extension 76 may suitably be of split construction and provided with screws 77 and 78, respectively, for clamping purposes. In this way the vertical position of the tube may be varied by vertical adjustment of the collar 75 while its angular position may be varied by clamping it in different positions within the extension 76. It will be observed that the point of connection between the member 71 and extension 67 is quite close to the axis of the pivotal connection between the ears 26 and arms 27. Thus only slight relative movement will take place between member 71 and extension 67 in adjusting the tension of the belt 43. This movement may readily be allowed by the flexibility of member 71 or by relative slippage between it and extension 67 or tube 72.

The character of the stream of cooling air developed by the blower and its mode of application to the needles should be governed by the principles set forth in the pending application of Charles F. Rubel, S. N. 433,740, filed on March 7, 1942. When these principles are observed it will be found that the speed of operation of the machine may be increased substantially without danger of overheating the needles, even in the stitching of relatively heavy materials such as denim, army twill, and the like. Moreover, this increase in speed is made possible without adding any appreciable extra load to the motor, so that a motor of conventional size and capacity may be embodied in the transmitter unit.

It will be apparent, particularly from Fig. I, that the improved construction permits rapid replacement of the belt 43. It is not necessary to

disconnect any part of the blower system in making such a belt replacement.

For the purpose of adequately lubricating the ball bearings 39 and 40, an oil cup 79 (Fig. III) may be mounted on the frame extension 42, this oil cup being adapted to deliver oil to and through an opening 80 in the sleeve 41 to the interior of the latter. Such lubricant will work its way along a spacing sleeve 81, carried by the shaft 38, to the bearings at the opposite ends of this sleeve. As will be seen from Fig. III, the clutch member 37, shaft 38, bearing units 39 and 40, sleeve 41, blower rotor hub 61 etc., sleeve 81 and pulley 14 form a unitary assembly. The parts are held assembled by the nut 45.

Flywheel 35 is preferably provided with vanes 82 on its inner surface adapted to create a flow of air from the interior of the motor housing outwardly around the end bonnet of the latter so as to maintain the motor in as cool a condition as possible. Similarly, a plurality of radially extending vanes 83 may be provided on the outer face of the flywheel for directing a stream of cooling air across the friction surfaces of the two clutch members.

It is believed that the operation of the improved construction will be clear from the foregoing detailed description. In the use of the sewing machine the operator will control the engagement of the clutch preferably from a foot treadle connected by a link 84 with one of the series of openings provided in the arm 55, as shown in Fig. I. Upon depressing the foot treadle and rocking the arm 55 downwardly the stud 48 will be rotated in an anti-clockwise direction, Fig. III, to shift the sleeve 41 toward the left. This will cause engagement of the driven clutch member 37 with the friction band 36. Such shifting of the sleeve 41 and shaft 38 is permitted by the clearance between the impeller and the plate 66c of the blower housing. As the clutch surfaces become worn the clutch member 37 must be shifted further toward the left to engage the clutch surfaces and the clearance between the impeller and the plate 66c may then become inadequate. In that case, it may become necessary to adjust the impeller axially along the supporting sleeve 60, toward the right in Fig. III. The set screw 62 need merely be loosened for this purpose. At the same time the brake member 59 should be adjusted, in the manner explained in applicants' prior pending application above mentioned so as to change the limit of movement of the clutch member toward the right in response to the action of spring 58. So also, when substantial wear of the clutch faces take place, it may be desirable to alter the adjustment of the set screws 57 so as to maintain the substantially horizontal position of the arm 55.

While an illustrative form of the invention has been disclosed in considerable detail, it will be understood that various changes may be made in the construction and arrangement of the various parts without departing from the general principles and scope of the invention.

What we claim is:

1. In apparatus of the class described a supporting structure, a sewing machine mounted on said structure, a motor and clutch unit carried by said structure beneath said sewing machine, said unit having a frame and a shiftable driven shaft, a bearing sleeve for said driven shaft carried by a portion of said frame, said sewing machine having stitch forming devices including a reciprocable needle, means including a pulley

secured to said shaft adjacent one end of said bearing sleeve said pulley being readily accessible for the application and removal of an endless belt for connecting said unit with said machine for driving said stitch forming devices, and needle cooling means comprising a blower and a conduit leading therefrom to the region of said needle, said blower having a housing fixedly secured to said portion of said frame and partly enclosing the end of said bearing sleeve remote from said one end thereof and a rotor mounted for axial adjustment on the driven shaft of said unit within said housing.

2. In apparatus of the class described a supporting structure, a sewing machine mounted on said structure, said sewing machine having stitch forming devices including a reciprocable needle, a motor and clutch unit carried by said structure, said unit comprising a frame having a shiftable driven shaft projecting from one end thereof, a pulley mounted on the projecting end of said shaft, said pulley being readily accessible for the application and removal of an endless belt, an endless belt connecting said pulley with said sewing machine for driving said stitch forming devices, a blower having a rotor secured to said shaft at a point on the inner side of said pulley and having a housing around said rotor secured to said frame, said rotor and housing being relatively adjustable in an axial direction and being axially shiftable relative to each other to engage and disengage the clutch, and a conduit for delivering air from said blower to the region of said reciprocable needle.

3. In apparatus of the class described a supporting structure, a sewing machine mounted on said structure, said sewing machine having stitch forming devices including a reciprocable needle, a motor and clutch unit carried by said structure, said unit comprising a frame having a bearing retaining portion, an axially shiftable shaft mounted in said bearing portion and having secured thereto a driven clutch member and a pulley, said pulley being at the end of said shaft and being readily accessible for the application and removal of an endless belt, an endless belt connecting said pulley with said sewing machine for driving said stitch forming devices, a blower having a rotor secured to said shaft at a point between said clutch member and said pulley and having a housing around said rotor secured to said frame, said rotor and housing being relatively adjustable in an axial direction and being axially shiftable relative to each other to engage and disengage the clutch, and a conduit for delivering air from said blower to the region of said reciprocable needle.

4. In apparatus of the class described a supporting structure, a sewing machine mounted on said structure, said sewing machine having stitch forming devices including a reciprocable needle, a motor and clutch unit carried by said structure, said unit comprising a frame having a detachable bearing retaining portion, an axially shiftable shaft and a bearing therefor mounted in said bearing retaining portion, said shaft having secured thereto a driven clutch member and a pulley, means connecting said pulley with said sewing machine for driving said stitch forming devices, means carried by said bearing retaining portion for shifting said shaft axially to engage the clutch, a blower having a rotor secured to said shaft at a point between said clutch member and said pulley and having a housing around said rotor secured to said detachable bearing retaining

portion of said frame, the construction and arrangement being such that said shaft, pulley, clutch member and blower may be removed from said unit with said detachable lower part, said rotor and housing being relatively adjustable in an axial direction, and a conduit for delivering air from said blower to the region of said reciprocable needle.

5. In apparatus of the class described a clutch unit comprising a frame having a bearing retaining portion, bearing means mounted therein, said portion having a detachable section so separable from the main part of said portion as to permit ready removal of said bearing means, an axially shiftable shaft carried by said bearing means, a driven clutch element adapted to be rendered effective upon shifting of said shaft in one direction, and a blower rendered effective upon such shifting of said shaft, said blower including an impeller mounted on said shaft and a housing mounted on said detachable section.

6. In apparatus of the class described a clutch unit comprising a frame having a bearing retaining portion, bearing means mounted therein, said portion having a detachable section so separable from the main part of said portion as to permit ready removal of said bearing means, an axially shiftable shaft carried by said bearing means, a driven clutch element at one end of said shaft adapted to be rendered effective upon shifting of said shaft in one direction, a pulley secured to said shaft at its opposite end, and a blower rendered effective upon such shifting of said shaft, said blower including an impeller mounted on said shaft between said clutch element and said pulley and a housing mounted on said detachable section.

7. In apparatus of the class described a clutch unit comprising a frame having a bearing retaining portion, bearing means including an axially shiftable sleeve mounted in said frame portion, a shaft journaled in said sleeve, a frictionally driven clutch element carried by said shaft and adapted to be rendered effective upon shifting of said sleeve in one direction, spring means for normally

retaining said clutch element in ineffective position, and means for shifting said sleeve in opposition to said spring means comprising rack teeth carried thereby, a rotary member having a toothed portion cooperating with said rack teeth, operating means for said rotary member, said member having flat surfaces, and screw means adapted to engage said flat surfaces to adjustably connect said operating means with said rotary member to vary the zone of action of said operating means.

8. In apparatus of the class described a clutch unit comprising a frame having a bearing retaining portion, bearing means including an axially shiftable sleeve mounted in said frame portion, a shaft journaled in said sleeve, a frictionally driven clutch element carried by said shaft and adapted to be rendered effective upon shifting of said sleeve in one direction, and means for shifting said sleeve comprising rack teeth carried thereby, a rotary member having a toothed portion cooperating with said rack teeth, and a portion providing a flat-sided radially extending projection, and operating means for said member surrounding said last mentioned portion and having adjustable screw means cooperating with the flat sides of said projection for varying the angular relation between said member and said operating means.
